UNITED STATES PATENT OFFICE.

WILLIAM W. FARNSWORTH, OF CHICAGO, ILLINOIS.

CLEANING APPARATUS.

Application filed October 31, 1921. Serial No. 511,696.

To all whom it may concern:

Be it known that I, WILLIAM W. FARNSWORTH, a citizen of the United States, residing at Chicago, in the county of Cook and 5 State of Illinois, have invented certain new and useful Improvements in Cleaning Apparatus, of which the following is a specification.

This invention relates to improvements in 10 cleaning apparatus particularly adapted though not necessarily limited in its use for cleaning carpets, rugs, floors, etc., and one of the objects of the invention is to provide an improved, portable device of this character embodying a nozzle by means of the 15 use of which the dirt and foreign matter will be dislodged from the surface and from within the body of the carpet by means of a pneumatic vibrator in the form of air currents operating in a direction substantially longitudinally of the length of the nozzle, and which air currents are applied to the surface for substantially the entire length of the nozzle.

20 A further object is to provide an improved nozzle having a narrow inlet slot and air receiving slots defining the lateral edges of the inlet slot and receiving air from the atmosphere, the inlet openings of the air 25 slots being disposed in such a position with relation to each other and to the respective slots that opposed air currents will be applied to the surface to be cleaned and adjacent the inlet slot of the nozzle, whereby 30 the opposed air currents will come into contact with each other beneath the inlet slot of the nozzle to cause a swirling motion of the air currents upon the surface of and within the body of the carpet for dislodging 35 and rooting out the dirt and foreign matter.

To the attainment of these ends and the accomplishment of other new and useful objects as will appear, the invention consists 40 in the features of novelty in substantially the construction, combination and arrangement of the several parts, hereinafter more fully described and claimed and shown in the accompanying drawing illustrating this invention and in which—

45 Figure 1 is a view partly in side elevation and partly in section and with parts broken away.

Figure 2 is a front elevation with parts broken away.

Figure 3 is a top plan view of a portion of 55 the nozzle.

Figure 4 is a bottom view of the nozzle showing the direction of the air currents.

Referring more particularly to the drawing the numeral 10 designates an air circulation device of any desired construction but preferably is of the well-known fan type having a discharge outlet 11 and to which outlet opening is connected a bag or receptacle 12 for receiving the dust, dirt and foreign matter. All of these parts may be of the ordinary and well-known construction.

55 The air circulation creating device is provided with an inlet opening 13 and a nozzle designated generally by the reference numeral 14, is connected with the apparatus by any suitable means and in such a manner that the inlet passage 15 of the nozzle will communicate with the inlet opening 13 of the casing of the air circulation creating 60 device 10.

65 The passage 15 is provided with an inlet opening 16 preferably in the form of a narrow slot which extends lengthwise of and for substantially the entire length of the 70 nozzle 14.

75 This passage 15 is provided with an inlet opening 16 preferably in the form of a narrow slot which extends lengthwise of and for substantially the entire length of the 80 nozzle 14. A portion of the nozzle adjacent the lower end thereof or the end which stands adjacent the surface to be cleaned is preferably enlarged so as to form two passages 17 and 18 85 on opposite sides of the passage 15, the passage 17 being provided with a discharge outlet opening 19 and the passage 18 is provided with a discharge outlet opening 20. The lower edges of the walls 21 and 22 of the 90 inlet passage 15 of the nozzle 14 terminate short of the lower edges of the outer walls 23—24 of the respective outlet openings 19 and 20 so that when the edges of the walls 23 and 24 contact with the surface to be 95 cleaned, the lower edges of the walls 21 and 22 will be spaced above such surface. With this arrangement the pile of the carpet will be permitted to stand uprightly while the lower edges of the walls 23 and 24 will depress the adjacent portions of the pile and thereby permit the air currents to be directed into the pile of the carpet.

100 The lower edges 25—26 of the respective walls 21 and 22 may be of any desired width so as to form laterally extended surfaces above the pile of the carpet or surface to be cleaned for the purpose of holding the air

currents against the surface. These surfaces 25 and 26 also serve as a means for causing the air currents to be compressed in a measure as they pass through the carpet beneath 5 the surfaces 25 and 26, thereby insuring a full force of operation against the surface and within the body of the carpet.

The inlet opening 27 of the passage 17 has communication with the atmosphere and 10 this opening 27 is offset with respect to the outlet opening of the passage 15 in a direction lengthwise of the nozzle and is preferably arranged adjacent one end of the nozzle, the upper wall 28 of the passage 17 15 inclining downwardly from the inlet opening 27 in a direction of and terminating adjacent the opposite end of the nozzle so that the air currents which are drawn in the opening 27 will be distributed substantially 20 equal, substantially throughout the entire length of the nozzle. The offsetting of the inlet opening 17 with respect to the passage 15 also serves as a means for causing the air currents which are admitted into the passage 17 to flow in a direction substantially 25 longitudinally of the length of the nozzle and will be delivered from the passage 17 through the outlet 19 beneath the surface 25 of the wall 21 with an abrupt change of direction of flow thereby causing a swirling action of the air against the surface.

The passage 18 arranged on the opposite side of the inlet opening 16 of the passage 17 is itself provided with an inlet opening 29 similar to the inlet opening 27. This inlet opening 29 is preferably arranged adjacent the end of the nozzle opposite to the end adjacent which the inlet opening 27 is arranged and the upper wall 30 of the passage 18 is also inclined downwardly from the inlet opening 29 to the end of the nozzle for the same purpose that the wall 18 of the passage 17 is inclined.

It will be manifest that the inlet openings 27 and 29 being offset with respect to each other and inasmuch as the upper walls 28 and 30 respectively of the passages 17 and 18 incline in directions opposite to each other, that air currents being admitted into the passages 27 and 29 will flow in opposite directions through the passages. As the air flows in from the atmosphere through the inlet opening 29 into the passage 18 it will 50 pass through the outlet opening 20 beneath the surface 26 of the wall 22 into the passage 15 and the inclined wall 30 will cause the incoming air currents to operate upon the surface throughout substantially the entire length of the nozzle.

The offsetting of the opening 29 of the passage 18 with respect to the outlet opening 15 of the nozzle will cause the air currents to change their direction of flow as they pass from beneath the surface 26 and thereby 60 operate upon the surface with a swirling

movement in a manner similar to the operation of the air currents from the passage 17 upon the surface to be cleaned.

It will be manifest that the inlet openings 27-29 are arranged adjacent opposite ends of the nozzle and on opposite sides of the outlet opening of the passage 15, and that the upper walls 28 and 30 respectively of the passages 17 and 18 incline downwardly from the opposite ends of the nozzle and in opposite directions, so that the air currents entering the inlet openings 27-29 will flow in opposite directions, and as these air currents pass beneath the respective surfaces 25-26 of the walls 21-22 their course of flow will be abruptly changed as they enter the inlet 16 of the passage 15. Inasmuch as these incoming air currents are flowing in opposite directions, and as they are delivered simultaneously into the inlet opening of the passage 15, they will clash or come in contact with each other in such a manner as to increase the swirling movement of the action of the air currents upon the surface beneath the inlet opening 16, and cause a violent agitation of the air currents upon the surface to be cleaned beneath the inlet opening 16, thereby operating as a pneumatic vibrator or agitator upon the surface being cleaned, with the result that the air currents will root down into the body of the carpet and dislodge all dirt and foreign matter held therein.

The dust and dirt will then be caught up by the suction created in the passage 15 of the nozzle 14 and will be delivered into the inlet opening of the air circulation creating device 10 from whence they will be delivered through the outlet opening 11 into the impurities collecting receptacle or bag 12.

In the present exemplification of this invention and as shown in the drawings two air passages are arranged one on each side of the inlet opening 16 but it is obvious that either one or the other of these passages may be omitted and the apparatus will operate efficiently with one of these passages.

While the preferred form of the invention has been herein shown and described it is to be understood that various changes may be made in the details of construction and in the arrangement of the several parts, within the scope of the claims, without departing from the spirit of this invention.

What is claimed as new is:-

1. A cleaning apparatus nozzle provided with a narrow inlet slot adapted to be closed by the surface to be cleaned, said nozzle having a discharge outlet, an air passage in the nozzle having an inlet opening adjacent one end of the nozzle, said passage having a continuous discharge narrow outlet opening adjacent and extending along the side of said slot, the upper wall of the said passage inclining downwardly from a point adja-

cent the inlet being constantly open thereof to a point in close proximity to the opposite end of the nozzle, the inlet of said passage opening to the outside air.

- 6 2. A cleaning apparatus nozzle provided with a narrow inlet slot adapted to be closed by the surface to be cleaned, said nozzle having a discharge outlet, an air passage in the nozzle having an air inlet opening, said passage having a continuous discharge narrow outlet opening adjacent and extending along the side of said slot, the upper wall of the passage inclining downwardly from a point adjacent the inlet opening thereof to a point 10 in proximity to the end of the nozzle, the outlet of said inlet slot and the inlet of said passage being offset from each other in directions lengthwise of the nozzle, the inlet of the said passage being constantly open 15 to the atmosphere.

3. A cleaning apparatus nozzle provided with a narrow inlet slot adapted to be closed by the surface to be cleaned, said nozzle having a discharge outlet, and means for supplying counter currents of outside air to the surface adjacent the said inlet slot, and in directions lengthwise of the said nozzle.

4. A cleaning apparatus nozzle provided with a narrow inlet slot adapted to be closed by the surface to be cleaned, said nozzle having a discharge outlet, and means for supplying counter currents of fluid to the surface adjacent the said inlet slot, and in directions lengthwise of the said nozzle.

35 5. A cleaning apparatus nozzle provided with a narrow inlet slot adapted to be closed by the surface to be cleaned, said nozzle having a discharge outlet, and means for supplying counter currents of outside air to the surface adjacent the said inlet slot, and in directions lengthwise of the said nozzle, the said means embodying air passages arranged adjacent the lateral edges of the said inlet slot, said passages having inlets individual thereto and open to the atmosphere.

6. A cleaning apparatus nozzle provided with a narrow inlet slot adapted to be closed by the surface to be cleaned, said nozzle having a discharge outlet, and means for supplying counter currents of outside air to the surface adjacent the said inlet slot, and in directions lengthwise of the said nozzle the said means embodying air passages arranged

adjacent the lateral edges of the said inlet slot and being open to the atmosphere, the 55 inlets of the said air passages being offset with respect to each other in directions lengthwise of the nozzle.

7. A cleaning apparatus nozzle provided with a narrow inlet slot adapted to be closed by the surface to be cleaned, said nozzle having a discharge outlet, and means for supplying counter currents of outside air to the surface adjacent the said inlet slot, the said means embodying air passages arranged adjacent the lateral edges of the said inlet slot and having inlets individual thereto and open to the atmosphere, the inlets of the said air passages and the said discharge outlet being offset from each other in directions 70 lengthwise of the nozzle.

8. A cleaning apparatus nozzle provided with a narrow inlet slot adapted to be closed by the surface to be cleaned, said nozzle having a discharge outlet, and means for supplying counter currents of atmospheric air to the surface adjacent the said inlet slot, the said means embodying air passages arranged adjacent the lateral edges of the said inlet slot and being open to the atmosphere, said discharge outlet and the inlets of the said passages being offset from each other in directions lengthwise of the nozzle, and the inlets of the said passages being also offset from each other in directions length- 85 wise of the nozzle.

9. A cleaning apparatus nozzle provided with a narrow inlet slot adapted to be closed by the surface to be cleaned, said nozzle having a discharge outlet, an air passage in the nozzle and discharging on each side of and towards the inlet slot, each of the air passages having an inlet opening adjacent one end of the nozzle and open to the atmosphere, the upper walls of the respective air passages inclining downwardly from the respective inlets to the opposite ends of the nozzle and in opposite directions, the said inlets of the air passages being offset from each other and with respect to the said discharge outlet in directions lengthwise of the nozzle.

In testimony whereof I have signed my name to this specification on this 27th day of October, A. D. 1921.

WILLIAM W. FARNSWORTH.

Certificate of Correction.

It is hereby certified that in Letters Patent No. 1,468,467, granted September 18, 1923, upon the application of William W. Farnsworth, of Chicago, Illinois, for an improvement in "Cleaning Apparatus," errors appear in the printed specification requiring correction as follows: Page 3, line 1, claim 1, for the words "being constantly open" read *opening*, and line 4, for the word "opening" read *being constantly open*; and that the said Letters Patent should be read with these corrections therein that the same may conform to the record of the case in the Patent Office.

Signed and sealed this 16th day of October, A. D., 1923.

[SEAL]

WM. A. KINNAN,
Acting Commissioner of Patents.
